ABSTRACT

A urinal cover including a flexible sheet of material having a periphery, a water supply attachment patch attached to the sheet adapted to be placed around a water supply pipe of a urinal, and an elastic strip sewn into a portion of the periphery of the sheet.

6 Claims, 2 Drawing Sheets

FIG. 1

FIG. 2

FIG. 3

FIG. 4

1

URINAL COVER

BACKGROUND OF THE INVENTION

1. Field of the Invention

The field of the invention relates generally to urinal covers. More specifically, the field of the invention relates to a disposable, compact urinal cover.

2. Description of Related Art

In practice, urinal covers are not widely used for taking malfunctioning urinals out of service. This is primarily due to the fact that prior art urinal covers are large, bulky and require reuse. Because it is desirable to limit the amount of space dedicated to storing janitorial supplies, large pre-formed urinal covers are undesirable. Additionally, because prior art urinal covers were made from hard plastic, they were not disposable. Rather they had to be cleaned in order to maintain sanitary conditions. Finally, because urinals have many different profiles hard plastic urinal covers either do not fit every type of urinal properly or specific urinal covers with certain shapes must be ordered by an end user.

For these reasons, urinal covers have not gained widespread acceptance despite the fact that urinal frequently become clogged and must be taken out of service.

BRIEF DESCRIPTION OF THE DRAWINGS

FIG. 1 is a view of a urinal cover before elastic has been sewn into the seams according to the present invention;

FIG. 2 is a view of a urinal cover after elastic has been sewn into the seams according to the present invention;

FIG. 3 is a water supply attachment patch according to the present invention; and

FIG. 4 is urinal cover placed on a urinal according to the present invention.

DESCRIPTION OF THE PREFERRED EMBODIMENT

While the invention is susceptible of embodiment in many different forms, there is shown in the drawings and described in detail preferred embodiments of the invention. It is to be understood that the present disclosure is to be considered only as an example of the principles of the invention. This disclosure is not intended to limit the broad aspect of the invention to the illustrated embodiments. The scope of protection should only be limited by the claims.

Referring to FIGS. 1 and 2, the present invention provides a urinal cover 10 made from a flat, generally rectangular sheet 12 of plastic having the corners rounded. The edges of the sheet of plastic are folded back upon the sheet 12 and a length of elastic 14 is sewn into the edge of the sheet 12. Glued to the sheet 12 is a water supply attachment patch 16. The water supply attachment patch 16 is preferable made from a resilient plastic or rubber material. Preferably, the water supply attachment patch 16 generally comprises a rectangular portion having a circular cutout 22 therein. Additionally, a V-shaped cutout 24 extends from a side of the patch 16 to the circular cutout 22. Because the cover 10 is made primarily of plastic and elastic, the cover 10 can be collapsed to take very little space when not in use and can be used disposably in order to avoid every having to clean the cover.

2

Referring to FIG. 3, conventional urinals 18 have a water supply pipe 20 coming from the top of the urinal 18. The bag is used to cover the urinal by attaching the water supply attachment patch 16 to the water supply pipe 20. Because the water supply attachment patch 16 is made from resilient material it resiliently deforms as it is pushed around the pipe 20 and retains itself upon the pipe 20 after installation. Next, the elastic 14 is stretched and placed around the outer periphery of the urinal 18. The elastic 14 contacts the outer periphery of the urinal 18 and holds the cover 10 to the urinal 18.

While the specific embodiments have been illustrated and described, numerous modifications come to mind without significantly departing from the spirit of the invention, and the scope of protection is only limited by the scope of the accompanying claims.

I claim:

1. A urinal cover comprising:
a flexible sheet of material having a periphery;
a water supply attachment patch attached to the sheet
adapted to be placed around a water supply pipe of a
urinal; where it deforms and retains itself upon the pipe
an elastic strip attached to a portion of the periphery of the
sheet; and

wherein the flexible sheet defines an opening in the
periphery over which said attachment patch is secured.

2. The urinal cover of claim 1 wherein the sheet is
generally rectangular and the corners of the generally rect-
angular sheet have been rounded.

3. A urinal cover comprising:
a flexible sheet of material having a periphery;
a water supply attachment patch attached to the sheet
adapted to be place around a water supply pipe of a
urinal at a location adjacent to the periphery of the
sheet;

an elastic strip sewn into a portion of the periphery of the
sheet; and

wherein the water supply attachment patch defines a
circular cutout and a V-shaped cutout to allow attach-
ment to the water supply pipe of the urinal.

4. A method of covering a urinal comprising:
providing a flexible sheet of material having a periphery
and an opening at a point along the periphery;
providing a water supply attachment patch attached to the
sheet over the opening;
providing an elastic strip attached to a portion of the
periphery;
attaching the water supply attachment patch to a water
supply pipe of the urinal such that the water supply pipe
extends through the opening of the sheet; and
expanding the elastic strip about the periphery of the
urinal.

5. The method of claim 4 wherein the sheet is generally
rectangular and the corners of the generally rectangular
sheet have been rounded.

6. The method of claim 4 wherein the water supply
attachment patch defines a circular cutout and a V-shaped
cutout to allow attachment to the water supply pipe of the
urinal.
